DOUBLE GARBAGE CAN STAND

George R. Youngblood and Oliver T. Ivey, Albany, Ga.

Application March 15, 1957, Serial No. 646,423

3 Claims. (Cl. 211—71)

This invention relates to stands for garbage or trash cans, and more particularly has reference to a garbage can stand adapted to support a pair of conventional garbage cans in side-by-side relation, in a manner to permit access to or movement of either can independently of the other.

A main object of the present invention is to provide a generally improved double garbage can stand, characterized by its simplicity of construction, its efficiency when in use, its ruggedness, and its particular adaptability to support garbage cans of different sizes in the compartments provided therefor.

Another object is to provide a double garbage can stand fabricated almost wholly from conventional bar stock, readily cut to the desired size and welded to provide a highly rigid, strong construction.

Yet another object is to provide a garbage can stand wherein the support for the garbage cans will extend continuously over the full length of the stand, as will the longitudinal, can-confining members associated with the support.

A further object is to so form the support for the garbage cans as to not only support the cans in elevated position, but also cause the support to constitute a longitudinal and transverse bracing means for the main frame of the device.

Another object is to provide a garbage can stand which will be readily anchored at any desired location, in a manner such as to prevent the stand from being overturned.

Other objects will appear from the following description, the claims appended thereto, and from the annexed drawing, in which like reference characters designate like parts throughout the several views, and wherein:

Figure 1 is a perspective view of a garbage can stand according to the invention;

Figure 2 is a transverse sectional view on line 2—2 of Figure 1; and

Figure 3 is a fragmentary longitudinal sectional view on line 3—3 of Figure 2.

Referring to the drawings in detail, the garbage can stand constituting the present invention includes a rectangular bottom frame 10 lying in a horizontal plane in contact with the ground surface G or other supporting surface. Bottom frame 10 is formed wholly of solid bar stock of square cross section in a preferred embodiment and includes straight, parallel longitudinal members 12 welded or otherwise fixedly connected at their ends to end or transverse members 14.

A top frame 16 lies in a horizontal plane, and is somewhat greater in length and width than the bottom frame. Top frame 16 includes longitudinal bars 18 welded at their ends to end bars 20. Fixedly connected between the corners of the top and bottom frames are corner posts 22 converging in a downward direction, due to the differences in the dimensions of the top and bottom frames. Medially between the opposite ends of the frames, intermediate posts 24 are fixedly connected at

2

their upper ends to the longitudinal members 18. Fixedly connected between the mid-length portions of the members 18 and extending horizontally, transversely of the top frame to define a partition is an intermediate cross bar 26.

Supported at its ends upon and welded or otherwise fixedly secured to the intermediate portions of the longitudinal members 12 of the bottom frame is a flat, wide lower cross bar 28. Welded to and projecting upwardly from bar 28 at opposite sides of the mid-length point thereof are short support plates 30. These are welded to the undersides of the mid-length portions of garbage can support bars 32 that extend in parallel relation longitudinally of the stand. Bars 32 are offset inwardly from the opposite sides of the framing structure as seen from Figure 2, and at their opposite ends are fixedly connected to cross braces 36 that are welded at their ends to and extend between the respective, corresponding corner posts 22. Transverse braces 34 are also fixedly connected between the members 32, inwardly from the end cross braces 36.

Centrally formed in the bar 28 is a smooth-walled opening, receiving an anchoring pin 38 having a head at its upper end, adapted to engage the bar 28. Pin 38 may be threaded, at its lower end, for engagement in a suitable support or for insuring its being firmly anchored in concrete or the like. In any event, the pin 38 is adapted to be extended into the supporting surface, to firmly anchor the stand against tilting either in a longitudinal or in a transverse direction.

By reason of the construction illustrated and described, the double garbage can stand is adapted to support side-by-side cans C in positions elevated above the ground surface G. Further, the cans may be of any size, that is, they could be 20-gallon cans, 31-gallons cans, etc.

The garbage cans, when supported upon the rack, are spaced apart by the divider or partitioning bar 26, and are supported wholly upon the support bars 32, 34. Bars 34 are extended transversely of and between bars 32 at locations particularly effective to support the cans without danger of collapse of the structure under the weight of the cans.

Further, the top frame and the partition 26 define side-by-side, upwardly opening compartments for the two supported garbage cans, the walls of the compartments being comparatively high so that the garbage cans may not be accidentally tilted or overturned.

The construction, as will be noted, is one in which the elevated support ledge means 32, 34, 36 for the garbage cans serves as a longitudinal and transverse bracing for the framing means 12, 16, 22, 24. In turn, the cross bar 28 and plates 30 serve to brace the support ledge assembly as well as the bottom frame. A particularly strong though inexpensive construction thus results.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claims.

What is claimed is:

1. A double garbage can stand comprising a horizontal, rectangular, elongated bottom frame; a horizontal, rectangular, elongated top frame; corner posts connected fixedly between the respective frames at the corners there-

of; partitioning means extending transversely of the frames intermediate their ends to define a pair of side-by-side, upwardly opening, can-receiving compartments; a support ledge assembly extending within said compartments in a position elevated above the bottom frame, comprising parallel, spaced support bars extending longitudinally within the stand inwardly from the sides of the stand to support a pair of garbage cans disposed within the compartments, and end cross bars fixedly connected between the extremities of the support bars and in turn fixedly connected between the posts of the opposite ends of the stand, said support ledge assemblies further including cross braces fixedly connected between the support bars within each compartment to rigidify the support ledge assemblies in the areas in which said assembly underlies the supported cans; and crossbracing means extending between opposite sides of the bottom frame medially between the ends of the bottom frame, comprising a wide, flat cross bar fixedly connected between the respective sides of the bottom frame and upwardly projecting support plates fixedly connected between the cross bar and the respective support bars.

2. A double garbage can stand comprising a horizontal, rectangular, elongated bottom frame; a horizontal, rectangular elongated top frame; corner posts connected fixedly between the respective frames at the corners thereof; partitioning means extending transversely of the frames intermediate their ends to define a pair of side-by-side, upwardly opening, can-receiving compartments; a support ledge assembly extending within said compartments in a position elevated above the bottom frame, comprising parallel, spaced support bars extending longitudinally within the stand inwardly from the sides of the stand to support a pair of garbage cans disposed within the compartments, and end cross bars fixedly connected between the extremities of the support bars and in turn fixedly connected between the posts of the opposite ends of the stand, said support ledge assemblies further including cross braces fixedly connected between the support bars within each compartment to rigidify the support ledge assemblies in the areas in which said assembly underlies the supported cans; crossbracing means extending between opposite sides of the bottom frame medially between the ends of the bottom frame, comprising a wide, flat cross bar fixedly connected between the respective sides of the bottom frame and upwardly projecting support plates fixedly connected between the cross bar and the respective support bars; and an anchoring pin extending through said cross bar at a location medially between the respective, upwardly projecting support plates.

3. A double garbage can stand comprising: open-center, rectangular, top and bottom frames each of which lies wholly in a horizontal plane, each of said frames including a single pair of straight, parallel, longitudinal members, and a single pair of end members each of

which is welded at its ends to the adjacent ends of and extends between the respective longitudinal members; corner posts terminating at their upper and lower ends in the planes of the top and bottom frames respectively, said posts being fixedly connected between the frames at the several corners of the frames; a single pair of intermediate posts, each intermediate post being extended between the mid-length portions of corresponding longitudinal members of the respective frames; a transverse partitioning bar in the plane of the top frame, fixedly connected between the mid-length portions of the longitudinal members of the top frame; a single horizontal cross bar extending between the longitudinal members of the bottom frame and having its ends disposed upon and fixedly connected to the mid-length portions of said longitudinal members of the bottom frame, each intermediate post being fixedly secured at its lower end to an adjacent end of the cross bar, and at its upper end to an adjacent longitudinal member of the top frame; a single pair of horizontal cross braces each of which is at an end of the stand and is connected between the corner posts at said end of the stand; a single pair of horizontal support bars extending fully from end-to-end of the frames in parallel relation to the longitudinal members, said support bars being spaced laterally inwardly from the respective longitudinal members at the corresponding sides of the stand and having their ends fixedly connected to the respective cross braces, the cross braces and support bars being all disposed in a common horizontal plane between the planes of the top and bottom frames; a single pair of support plates each of which extends upwardly from the cross bar below one of the support bars and is fixedly connected between the cross bar and the mid-length point of the adjacent support bar; a single pair of horizontal transverse braces each of which is fixedly connected between the support bars in the plane thereof approximately midway between said mid-length points of the support bars and the adjacent ends of the support bars; and an anchoring pin extending downwardly from and engaged with the cross bar midway between the support plates for engagement in the ground surface.
